EDWIN EMIL LINDENBEIN, OF ALLENTEWON, PENNSYLVANIA.

ROTARY ENGINE.

1,293,820.

Specification of Letters Patent. Patented Feb. 11, 1919.

Application filed August 30, 1916. Serial No. 117,753.

To all whom it may concern:

Be it known that I, EDWIN E. LINDENBEIN, a subject of the German Emperor, residing at Allentown, in the county of Lehigh 5 and State of Pennsylvania, have invented certain new and useful Improvements in Rotary Engines, of which the following is a specification.

This invention relates to rotary steam engines and it is the primary object of the invention to provide a steam engine having an improved form of valve control means, whereby, the motive fluid will be automatically admitted to and from the rotor or 10 steam chamber, thus, driving the rotor.

The nature of the invention more explicitly set forth, resides in the construction of the rotor or steam chamber, and the provision of the rotary cut-off valve; the rotor 15 chamber being arranged eccentric to the axis of the rotor, while the rotary cutoff valve is carried by the rotor shaft and is provided with a plurality of ports therein, which alternately register with the intake and exhaust ports of the engine, consequently, automatically controlling the passage of the steam to and from the rotor or steam chamber.

The invention also aims to provide auxiliary exhaust ports, these ports being arranged in the engine housing or casing, whereby, the exhaust of the spent steam 20 will be facilitated.

The invention also embraces novelly 25 formed intake and exhaust ports, the same being of such contour as will cause the ingress and egress of steam to be cut off.

The improvements in the details and arrangement of parts will be apparent from an 30 inspection of the accompanying drawings, in connection with the specific description hereinafter contained, and wherein the preferred embodiment of the invention is illustrated for the purpose of imparting a full 35 understanding of the invention.

In the drawings:—

Figure 1 is a vertical transverse section through my improved steam engine taken on the line 1—1 of Fig. 2.

Fig. 2 is a side elevation thereof with parts of the device removed and showing the arrangement of the rotor chamber and the rotor with its sliding abutment as shown on the line 2—2 of Fig. 1, looking in the 50 direction of the arrows.

Fig. 3 is a side elevation partly in section showing the arrangement of the intake and exhaust ports within one wall of the casing as shown on the line 3—3 of Fig. 1 looking in the direction of the arrows. 60

Fig. 4 is a side elevation partly in section showing the spring packing for the sliding abutment.

Fig. 5 is a detail in perspective of the 65 rotor chamber packing strip.

Referring more specifically to the drawings, wherein like reference numerals designate corresponding parts in the several views, I provide a rotor housing or casing, indicating the same in its entirety by the 70 numeral 1, which casing comprises a substantially cylindrical body having laterally offset seats 2 and 3 arranged upon the base thereof, thus, providing for means whereby the same may be secured to a suitable base 75 or other support by means of bolts or other fastening devices as at 4. Circumferentially extending flanges 5 are arranged upon either side of the casing and have arranged therein openings generally indicated as 6, for receiving securing screws 7, the purpose of which will be subsequently described. A rotor chamber 8 is arranged within the casing 1 and has arranged in the upper portion of its wall, a series of openings 9, these 80 openings serving as auxiliary exhausting ports whereby the spent steam may be passed from the same. Circular plates 10 and 11 are received by the side portions of the casing 1 and are secured thereto through the medium of the screws 7, which screws are passed through the openings 6 as arranged in the circumferential flanges 5, into complementally threaded openings, formed within the annular extending portions 12 85 and 13 of the plates 10 and 11, respectively. It is to be noted that the plates 10 and 11 are of the double wall type and have arranged upon their inner or adjacent faces, annular recesses 14 and 15, the purpose of 90 which will be subsequently apparent. Bearing openings 16 and 17 are formed in the plates 10 and 11 and as will be obvious, these openings are eccentric to the longitudinal axis of the rotor chamber 8, this 95 being attributable to the arrangement of the said chamber in relation to the side portions of the casing 1. The plate 10 has arranged within its inner wall, tapered slots 18 and 19, the former communicating with the in- 100

110

take pipe 20 and constituting the intake port, while the latter communicates with the exhaust pipe or opening 20 and constitutes the exhaust port.

- 5 A rotor 22 is arranged within the rotor chamber 8 and is provided with stub supporting shafts 23 and 24, which shafts are received by the openings 16 and 17 as arranged within the bearing plates 10 and 11.
- 10 The rotor 22 is hollow and has formed therein a diametrically extending slot 25, which receives therethrough a sliding element 26, the opposite extremities of which serve as abutments for the steam or other motive fluid. The outer extremities of the sliding element 26 are bifurcated as at 27 and 28 and have arranged therein, packing strips 29, which strips are normally held in engagement with the adjacent face of the
- 15 rotor chamber by means of arcuate springs 30 which are arranged in said bifurcated portions 27 and 28 beneath their respective packing strips 29. The circumferentially extending wall of the rotor chamber has arranged therein, a packing strip 31 to afford a fluid tight joint between the intake and exhaust portions of the rotor chamber.

Referring now to the valve control mechanism, this construction provides for means whereby the ingress and egress of steam to and from the rotor chamber 8 is controlled, I affix to one side of the rotor 22, a bearing plate 32, this plate being snugly received by the side portions of the casing 1 in suitably recessed portions formed therein. Set screws 33 are passed through the plate at points in proximity to the center thereof and are received by the adjacent portions of the rotor 22, thus, securely affixing the same to the latter. The heads of the set screws 33 extend beyond the outer face of the bearing plate 32 and are received by the annular recessed portions 14. Upon the remaining side of the rotor, I affix a similar disk-like plate 34, by means of set screws 35, which are in turn received by the adjacent portion of the rotor. Within the plate 34, I arrange a pair of diametrically arranged tapering slots 36 and 37, these slots being adapted for alternate registration with the intake and exhaust ports 18 and 19, whereby, the necessary motive fluid may be introduced into the rotor chamber 8 and may be then exhausted therefrom. The heads of the set screws 35 are received by the annular recessed portions 15 as arranged within the plate 10, thus, permitting the rotation of the rotor and the plates. By providing the tapering slots 36 and 37 within the rotatable disk 34, it is evident, that the steam will be admitted to the rotor chamber from the intake port 18 and will be exhausted therefrom through the exhaust port 19 and then through the pipe 21, into the atmosphere.

The operation of the construction may be reviewed as follows:

Steam is passed through the pipe 20 into the double walled plate 10 and is then introduced through the intake port 18 as arranged in said plate into the rotor or steam chamber 8, whereupon, it engages with the adjacent abutment as formed upon the slideable element 26 and forces the rotor around upon its axis. Upon continued travel of the rotor, one of the tapering slots 36 or 37 will register with the tapering exhaust port 19 and will permit a larger portion of the dead steam to be exhausted therethrough and passed through the exhaust pipe 21 and into the atmosphere. Before a complete exhaustion of the dead steam is had, it will be obvious that the diametrically positioned openings arranged within the heads 34 will register with the intake port 18 and that a fresh charge of live steam is admitted to the rotor chamber 8 and engages the remaining extremity of the sliding element 26, which constitutes an efficient abutment therefor, and causes the rotation of the rotor 22 to be continuous. It is evident, that when a complete exhaustion of the dead steam has been made, the slideable element 26, will assume a substantially vertical position within the rotor chamber 8 and the upper portion thereof will be flush with the periphery of the rotor 22, thus, allowing the same to pass the joint adjacent the packing strips 31. As rotation continues, that portion of the slideable element 26, as had been previously flush with the rotor 22, will be extended and will at all times be in contact with the circumferential wall of the chamber 8, this being attributable to the eccentric arrangement of the rotor 22 with relation to the rotor chamber 8. At this point, the intake opening as adjacent this portion of the slideable element 26 will register with the intake port 18 and admit a charge of steam into the chamber 8, while the dead steam is being exhausted therefrom.

While I have herein disclosed the specific embodiment of the invention, it will be apparent to persons skilled in the art, that the invention is capable of embodiment in other forms and devices differing in detail and arrangement from that shown, as may be in keeping with the hereto appended claims.

Having thus described the invention, what is claimed is:

1. In a rotary engine, a rotor casing, a rotor working within a chamber therein, said chamber being arranged eccentric to the axis of the rotor, a sliding abutment carried by the rotor, intake and exhaust ports arranged in said casing, and a disk movable with the rotor having diametrically positioned ports arranged in proximity to said sliding abutment formed therein and alter- 130

nately registerable with the intake and exhaust ports of the casing and communicating with the rotor chamber.

2. In a rotary engine, a rotor casing, a rotor working within a chamber therein, said chamber being arranged eccentric to the axis of the rotor, tapering slots formed within said casing and constituting intake and exhaust ports thereof, a slideable element carried by said rotor, the opposite extremities of said element providing for abutments, and a disk movable with the rotor having tapering slots formed therein and arranged in diametrically opposite positions adjacent said sliding element, said slots being alternately registerable within said intake and exhaust ports of the casing and communicating with the rotor chamber.
3. In a rotary engine, the combination of a casing including a rotor chamber, a rotor

rotatably mounted within said chamber, a one-piece sliding element movably mounted through said rotor, a plate connected to one side of said rotor, a disk connected to the opposite side of said rotor, said sliding element being movably mounted between said plate and disk, thus reducing frictional action upon said sliding element as the same is reciprocated when said rotor is rotating, said casing having intake and exhaust ports formed therethrough, said disk having intake and exhaust ports formed therethrough, thus causing the ports of said disk to alternately register with the ports of said casing.

In testimony whereof I affix my signature in presence of two witnesses.

EDWIN EMIL LINDENBEIN.
